CLAIM

We claim the ornamental design for a trainer device, as shown and described.

DESCRIPTION

FIG. 1 is an top rear perspective view of a trainer device; FIG. 2 is a top front perspective view of the design shown in FIG. 1;

FIG. 3 is a front elevation view of the design shown in FIG. 1;

FIG. 4 is a rear elevation view of the design shown in FIG. 1;

FIG. 5 is a right side elevation view of the design shown in FIG. 1;

FIG. 6 is a left side elevation view of the design shown in FIG. 1;

FIG. 7 is a top plan view of the design shown in FIG. 1; and, FIG. 8 is a bottom plan view of the design shown in FIG. 1. The broken lines depict portions of the trainer device that shown form no part of the claimed design.
